[57] CLAIM

The ornamental design for an electronic copying machine
with facsimile, as shown.

DESCRIPTION

FIG. 1 is a perspective view of the top, front and right side
of an electronic copying machine with facsimile showing
our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof; and,

FIG. 7 is a bottom plan view thereof.
